RAILWAY TRACK GAUGE

André Ernest Mauzin, Paris, France

Application January 19, 1933, Serial No. 652,576
In France November 28, 1932

7 Claims. (Cl. 33—144)

The present invention relates to a device for measuring the gauge of railway track and the out-of-line of the rails in a horizontal plane by means of shoes rubbing against the rails.

5 The accompanying drawings show, by way of example, a construction according to the invention.

Figure 1 is a diagrammatic representation of a carriage for supporting and bringing the shoe 10 into contact with the rail.

Fig. 2 is a diagrammatic representation of the mechanism employed for bringing the shoe into a position of contact with the rail when for any reason the shoe has slipped over the rail toward 15 the exterior.

Fig. 3a is a perspective view of the shoe which is brought into contact with the rail.

Fig. 3b is a similar view of a shoe positioned in its support in which it may be oscillated.

20 Fig. 3c is another corresponding view of the shoe and its support positioned on a carriage.

Fig. 4 is a perspective view of a modification which provides for the oscillation of the shoe and the bringing of the same out of contact with the 25 rail.

Fig. 5 is a diagrammatic arrangement of apparatus for measuring the gauge of the rails.

Fig. 6 is a diagrammatic arrangement of apparatus for measuring the out of line of a rail 30 of a railway track.

Each shoe comprises a rail-contacting element 1 (Fig. 1) which is light and of small width, and is carried by a carriage 3 (Fig. 1) movable in a direction at right angles to the rail on a frame 5 35 (Fig. 1) fixed to the frame of the vehicle carrying the apparatus. A spring 6 (Fig. 1) pulls the carriage towards the rail.

As shown in Fig. 2, means are provided for 40 moving the carriage 3 in a direction toward the right after it has been moved to its extreme left-hand position. Movement of the carriage to the right of Fig. 2 is effected by means of a chain *m* or other transmission element which connects the carriage with the movable element of a shifting mechanism contained in the housing *h*. The shifting mechanism may consist of an electro- 45 magnetic device or of a piston movable in a cylinder by compressed air, the flow of which is controlled electrically. In either event, control 50 of the shifting mechanism is effected electrically by means of the electrical circuit including the contact 32 and the shiftable rod *b*.

The frame 5 is electrically connected by conductor *k* with one terminal of the shifting mechanism in housing *h* and the other terminal is

connected by conductor *j*, battery *g* and conductor *f* with one end of the sliding rod *b*. The other end of the rod *b* carries a contact *e* which is adapted to be moved into engagement with the contact point 32 mounted on frame 5, thereby completing the circuit. Movement of the rod *b* is effected by engagement of a projection *a* carried on the carriage 3 with projections *c* and *d* formed on the rod *b*. In operation, upon the carriage 3 being moved to its extreme left position by means of the spring 6, the projection *a* on carriage 3 engages the projection *c* on the rod *b* and moves the latter to bring contact point *e* into conductive engagement with the contact point 32. Upon thus completing the control circuit, the shifting mechanism is actuated to cause the carriage 3 to be moved to its extreme right-hand position. When the carriage 3 is moved to its extreme right-hand position, the projection *a* on the carriage engages the projection *d* 20 on the rod *b* and shifts the rod *b* to its right-hand position, breaking the connection between contact points *e* and 32. Upon thus breaking the circuit, the shifting mechanism is deenergized and the spring 6 will draw the carriage 3 to a 25 position whereby the shoe 1 will again engage the side of the rail. In passing over the rail, the rail-contacting shoe pivots about a horizontal pin 8 (Fig. 1) provided for this purpose and passes above the rail. The rail-contacting element then descends again and bears against a stop 10 (Fig. 1).

In addition to this possible displacement of the rail-contacting element, a displacement of the said element in the vertical plane is also provided, so that if the necessity arises, it may be withdrawn within the clearance limit prescribed on railways, that is to say, to a predetermined distance above the plane of the rolling surface of the rails. The said displacement may be effected 40 by means of a displacement of the rail-contacting element relatively to the carriage or of the carriage relatively to the frame of the car.

In the case where the rail-contacting element is displaced relative to the carriage, the rail-contacting element carries two pins 12, 13 (Fig. 3a) serving to support it within a casing 14 (Fig. 3b), where it is held in its lower position by means of springs 15, 16 (Fig. 3b).

In the first place, it will be seen that in order 50 to move the rail-contacting element out of its normal vertical position, it is necessary to apply a certain minimum effort thereon which will overcome the force exerted by the springs 15 and 16 and that, secondly, if the said effort is exceeded, 55

the rail-contacting element, by turning about one of its pins 12 or 13 or by raising vertically, is able to come within the clearance limit and clear the obstacles of the track, the casing itself being fixed by construction above the clearance limit.

The casing is fixed to the carriage by means of a hinge pin 17, 18 (Fig. 3) which is the same as the previously indicated pin 8 (Fig. 1).

The carriage consists of two triangularly arranged arms 21 connected together and having their free ends connected to the pins 17 and 18. Bracing rods 19, 20, and 26 impart rigidity to the frame. The ends of members 21 connected to the pins 17 and 18 are enlarged and provided with bores which serve as bearings to receive said pins. It will be noted from Fig. 3c that at the joint connecting the joined ends of members 21, there is provided an enlargement having a bore 22 therein. As shown in Fig. 6, a guide rod 82 passes through the bore 22 for guiding the carriage in its travel. In addition, it will be noted that the pins 17 and 18 serve as axles for pulleys 23 and 24, respectively, which roll on a pair of rails 83, clearly shown in Fig. 6.

In order to maintain the rail-contacting element in a vertical position, a stop linkage is provided. As shown in Fig. 3c, this linkage consists of a vertical link 19 carried by a rod 19' which, in turn, is supported by the carriage members 21. A second link 20 is supported by a rod 20' which is also carried by the members 21 of the carriage. The lower free ends of the links 19 and 20 are connected by a link 84, one end of which is adapted to engage the casing 14 of the rail-contacting member. A spring 85 has one end connected to a rod 86 supported by the members 21 and has its other end connected to a pin 87 carried by the link 84. The rod 86 and pin 87 are so positioned that the spring tends to shift the link 84 to the left of Fig. 3c. In order to prevent link 84 under the action of spring 85 from shifting the casing 14 toward the left of Fig. 3c beyond a vertical position, link 20 is provided with a projection 88 which cooperates with an extension 84' of link 84. By engagement of the projection 88 with projection 84' the shifting of bar 84 toward the left of Fig. 3c under the action of spring 85 is limited. However, the shifting of link 84 to the right of Fig. 3c is not limited and is resisted by the action of spring 85. If, for any reason, during the operation of the device the rail-contacting element is shifted to the right, the stop linkage will give under the action of spring 85 and permit shifting to the right. The spring 85, however, normally exerts a sufficient force to maintain the rail-contacting element in a vertical position.

In the case where the carriage is moved relatively to the frame of the car, the rail-contacting element carries two rods 55 and 56 which are the axles of two pulleys 57 and 58 (Fig. 4). The said two pulleys are adapted to run within a framework constituted by four rods 59, 60, 61, and 62 (Fig. 4). The said framework is guided vertically at both ends by supports 80 fixed to the frame 81 of the vehicle and is urged downwardly by springs 63 and 64 (Fig. 4). A triangle 65, 66 connects the axles of the pulleys 57, 58 (Fig. 4) to a slide block 67 sliding along a rod. The rail-contacting element is held in the vertical position by means of a stop linkage 70, 71 similar to that shown in Fig. 3.

A flexible tube (not shown) carries oil between the rail-contacting element and the rail and ensures continuous lubrication.

The measurement of the gauge or distance between the rails is effected as follows (see Fig. 5):

Two shoes running on one and the same frame at right angles to the axis of the track rub against each rail. The variation in the distance between the rails is given by the variation in the distance between the shoes.

In the case in which the frame supporting the shoes undergoes a relative displacement with respect to the recording apparatus recording the gauge of the track (for example, in the case in which the shoes are mounted on the frame of the bogie or truck and the recording apparatus is mounted on the body of the vehicle), the following device may be employed.

A cable connects the two carriages and passes over the pulleys 25, 26, 27, 28, 29, 30. A spring fixed to the body of the vehicle urges the pulley 27 and draws the carriages towards the exterior of the track by means of the cable.

The pulleys 25, 26, 29, 30 are fixed to the frame supporting the carriage, while the pulley 28 is held at an invariable vertical distance from the recording apparatus by means of a bar fixed by one end to the recording apparatus by means of a universal joint, and sliding by the other end in a guide fixed to the frame of the apparatus proper.

The vertical displacement of the pulley 27 relatively to the body of the vehicle gives half the variation in the distance between the rails.

The recording of the out-of-line of the rails in the horizontal plane is effected as follows (see Fig. 6):

Three shoes rub on one and the same rail. A cable starting from the shoe 41 passes over the pulleys 50, 51 and is fixed to one end 44 of a lever. A cable starting from the shoe 42 passes over the pulleys 54, 55 and is fixed to the other end 46 of the same lever. A cable 43 starting from the shoe 43 passes over the pulleys 52, 53, traverses the same lever at the point 45, passes inside a "Bowden" sheath 48 and is finally drawn by a spring 49. The stylus S is carried by cable 43' which serves to shift the same over the record sheet to trace a curve thereon.

The ratio of the distance between the points 44, 46 to the distance between the points 45, 46 is equal to the ratio of the distance between the shoes 41, 42 to the distance between the shoes 42, 43.

The "Bowden" sheath is connected at one end to the lever at the point 45 and at the other end to a fixed point on the recording apparatus. Since the fixed end of the sheath 48 is on the record support, relative movement between the cable 43' and sheath will cause stylus S to move over the record sheet. The end of sheath 48 attached to lever 44-46 is free to move with said lever.

With this arrangement, movement of all shoes 41, 42, and 43 in the same direction will produce a movement of lever 44-46, but so long as there is no relative out-of-line movement between the shoes the stylus S will not be moved.

The entire structure is mounted on the platform 89 of a car.

Having now particularly described and ascertained the nature of my said invention and in what manner the same is to be performed, I declare that what I claim is:

1. An apparatus for obtaining an indication of the out-of-line of a railway rail and transmitting the indication to a recording station, comprising three spaced shoes supported in contact with one

side of the rail and adapted to be shifted laterally by defects in the alignment of the rail, means for transmitting movement of the two outside shoes to two ends of a floating lever, a Bowden sheath having one end connected to the fulcrum of the lever, and a wire passing through said sheath having one end connected to the central shoe and the other end attached to an anchored spring, a stylus attached to said wire adjacent its point of connection to the spring, the other end of said Bowden sheath being connected to a record-support over which said stylus moves.

2. An apparatus for obtaining an indication of the out-of-line of a railway rail and transmitting the indication to a recording station, comprising three spaced shoes supported in contact with one side of the rail and adapted to be shifted laterally by defects in the alignment of the rail, means for transmitting movement of the two outside shoes to two ends of a floating lever, a Bowden sheath having one end connected to the fulcrum of the lever, a wire passing through said sheath having one end connected to the central shoe and the other end attached to an anchored spring, a stylus attached to said wire adjacent its point of connection to the spring, the other end of said Bowden sheath being connected to a record support over which said stylus moves, resilient means urging said shoes against the side of the rail, and means operable upon slipping of a shoe over the rail for returning it to its operative position.

3. An apparatus for obtaining an indication of the out-of-line of a railway rail and transmitting the indication to a recording station, comprising three spaced shoes supported in contact with one side of the rail and adapted to be shifted laterally by defects in the alignment of the rail, means for transmitting movement of the two outside shoes to two ends of a floating lever, a Bowden sheath having one end connected to the fulcrum of the lever, a wire passing through said sheath having one end connected to the central shoe and the other end attached to an anchored spring, a stylus attached to said wire adjacent its point of connection to the spring, the other end of said Bowden sheath being connected to a record support over which said stylus moves, each of said shoes being vertically slidably mounted in swinging supports mounted on laterally movable carriages, and resilient means urging said shoes downward relative to said supports.

4. An apparatus for obtaining an indication of the out-of-line of a railway rail and transmitting the indication to a recording station, comprising three spaced shoes supported in contact with one side of the rail and adapted to be shifted laterally by defects in the alignment of the rail, means for transmitting movement of the two outside shoes to two ends of a floating lever, a Bowden sheath having one end connected to the fulcrum of the lever, and a wire passing through said sheath having one end connected to the central shoe and the other end attached to an anchored spring, a stylus attached to said wire adjacent its point of connection to the spring, the other end of said Bowden sheath being connected to a record support over which said stylus moves, each of said shoes being laterally slidably mounted in carriages positioned for vertical oscillation.

5. An apparatus for obtaining an indication of the out-of-line of a railway rail and transmit-

ting the indication to a recording station, comprising three spaced shoes supported in contact with one side of the rail and adapted to be shifted laterally by defects in the alignment of the rail, means for transmitting movement of the two outside shoes to two ends of a floating lever, a Bowden sheath having one end connected to the fulcrum of the lever, a wire passing through said sheath having one end connected to the central shoe and the other end attached to an anchored spring, a stylus attached to said wire adjacent its point of connection to the spring, the other end of said Bowden sheath being connected to a record support over which said stylus moves, a laterally movable carriage supporting each shoe, resilient means urging the carriage to a position to bring the shoe into contact with one side of the rail, and means operable upon slipping of the shoe over the rail for energizing a motor for returning the carriage to its operative position.

6. An apparatus for obtaining an indication of the out-of-line of a railway rail and transmitting the indication to a recording station, comprising three spaced shoes supported in contact with one side of the rail and adapted to be shifted laterally by defects in the alignment of the rail, means for transmitting movement of the two outside shoes to two ends of a floating lever, a Bowden sheath having one end connected to the fulcrum of the lever, a wire passing through said sheath having one end connected to the central shoe and the other end attached to an anchored spring, a stylus attached to said wire adjacent its point of connection to the spring, the other end of said Bowden sheath being connected to a record support over which said stylus moves, a laterally movable carriage supporting each shoe, resilient means urging the carriage to a position to bring the shoe into contact with one side of the rail, means operable upon slipping of the shoe over the rail for completing an electric circuit to effect movement of the carriage against the resilient means, and means operable upon moving of the carriage to an extreme position for breaking the electrical circuit and thereby permitting the carriage to be returned by the resilient means to its operative position.

7. An apparatus for obtaining an indication of the out-of-line of a railway rail and transmitting the indication to a recording station, comprising three spaced shoes supported in contact with one side of the rail and adapted to be shifted laterally by defects in the alignment of the rail, means for transmitting movement of the two outside shoes to two ends of a floating lever, a Bowden sheath having one end connected to the fulcrum of the lever, a wire passing through said sheath having one end connected to the central shoe and the other end attached to an anchored spring, a stylus attached to said wire adjacent its point of connection to the spring, the other end of said Bowden sheath being connected to a record support over which said stylus moves, a vertically movable carriage for each shoe having laterally extending tracks formed thereon, a frame for supporting a shoe, and means for movably mounting said shoe supporting frame for lateral movement on the tracks of said carriage.
